UNITED STATES PATENT OFFICE.

JOHN DRESSEL, OF INDIANAPOLIS, INDIANA.

FLOATLESS CARBURETER.

1,126,159.

Specification of Letters Patent. Patented Jan. 26, 1915.

Application filed February 24, 1914. Serial No. 820,682.

To all whom it may concern:

Be it known that I, JOHN DRESSEL, a citizen of the United States, residing at Indianapolis, in the county of Marion and State of Indiana, have invented a new and useful Floatless Carbureter, of which the following is a specification.

My invention relates to improvements in carbureters and the object of my invention is to provide a floatless carbureter of simple design and adjustment into which a volatile liquid is injected in a fine spray, such as is suitable to be readily vaporized. The carbureter as described in the annexed drawings and specifications will also give a greater efficiency to the motor and will be a more economical device to operate, as it will give increased power while still using a smaller amount of gasoline.

With the foregoing and other objects in view which will appear as the description proceeds, the invention resides in the combination and arrangement of parts, and in the details of construction hereinafter described and claimed, it being understood that changes in the precise embodiment of the invention herein disclosed can be made within the scope of what is claimed without departing from the spirit of the invention.

In the drawings there is illustrated a vertical central sectional view through the complete carbureter.

Similar letters of reference refer to similar parts throughout the drawings.

In detail 10 is a mixing chamber of the carbureter; 11 is a butterfly valve for adjusting the flow of gas to the intake manifold; 12 is the air intake valve; 13 is a nozzle provided with an orifice; 14, through which the gasoline is sprayed.

The size of the orifice 14 is adjusted by the needle 15 by screwing it one way or the other as may be desired in the sleeve 16, a hollow tube 17 is secured to the mixing chamber 10, and at the lower end of this tube is secured a valve housing 18. The lower end of the valve housing 18 is threaded for a pipe connection from the gasoline feed pipe. There is an opening 19, through which the gasoline, or similar liquid, flows when the valve 20 is unseated.

The valve 20 is supported by a rod 21, the upper end of which has a head 22, which is held in a receptacle 23, into which is secured a plunger 24, made preferably

of light material. The valve 21 is kept in alignment with its seat by a guide 25, which is also a stuffing box and which is secured in the valve housing 18 at its upper end. 60 The valve 20 has a flange 26, and between this flange and the lower side of the valve guide 25 is a coil spring 27, which is adapted to return the valve 20 to its seat after having been opened. Near the lower end 65 of the housing 18 is a gasoline outlet for supplying the nozzle 13 with gasoline, comprising of pipe connections 29 and tube 30 and the projection of the mixing chamber 31. 70

The operation is as follows: When the motor is started, the suction of the piston, or pistons, of the engine creates a vacuum in the manifold and mixing chamber 10, thus causing the plunger 24 to rise in the 75 tube 17, and through the connections heretofore described, the plunger raises the valve 20 from its seat, allowing the gasoline to flow from the feed pipe to the inside of the valve housing 18, from which it flows 80 through the outlet pipe to the nozzle 13 and is sprayed into the mixing chamber 10, where it is vaporized and mixed with the air flowing through the air intake 12 into the mixing chamber, and the gas thus 85 formed flows through the intake manifold to the engine. The valve 20 will remain unseated as long as the engine continues running and allows the gasoline to flow continuously to the nozzle. 90

What I claim as my invention and desire to secure by Letters Patent is:

1. A carbureter, including a cylindrical casing open at one end and having an air inlet opening at one side intermediate of its ends, a fuel jet disposed in the casing at a point adjacent to the air inlet opening, a pipe leading from the jet and to a point below the sealed end of the casing, a valve casing carried upon the sealed end of the 100 casing and in communication with said pipe, said valve casing being coaxial with the axis of the casing, a conical valve mounted in said casing for vertical movement, a spring mounted therein for closing 105 said valve, a stem connected to said valve and projecting into the casing through the sealed end thereof, a vacuum actuated plunger mounted in the sealed end of the casing below the air inlet opening, and a loose 110 coupling connecting the stem of the valve to said plunger.

2. A carbureter, including a cylindrical casing open at one end and having an air inlet opening at one side intermediate of its ends, a fuel jet disposed in the casing at a point adjacent to the air inlet opening, a pipe leading from the jet and to a point below the sealed end of the casing, a valve casing carried upon the sealed end of the casing and in communication with said pipe, said valve casing being coaxial with the axis of the casing, a conical valve mounted in said casing for vertical movement, a spring mounted therein for closing said valve, a stem connected to said valve and projecting into the casing through the sealed end thereof, a vacuum actuated plun-

ger mounted for reciprocation within the sealed end of the casing at a point below the air inlet opening thereof, a stud carried concentrically of and depending from the under side of the plunger, a cap fitting thereupon and provided with a chamber, said cap being provided with an opening to receive the stem of the valve, and a head fixed upon the stem of the valve and mounted in the chamber of the cap and forming therewith a loose connection between the plunger and valve. 20 25

JOHN DRESSEL.
